(21) Appl. No.: **29/409,009**

(57) **CLAIM**

(22) Filed: **Dec. 20, 2011**

The ornamental design for a pull tab of a slider for a slide fastener, as shown and described.

(30) **Foreign Application Priority Data**

Jun. 28, 2011 (JP) 2011-014641

DESCRIPTION

(51) **LOC (9) Cl.** **02-07**

FIG. 1 is a perspective view of the top, front and right side of a pull tab of a slider for slide fastener showing my (our) new design;

(52) **U.S. Cl.** **D11/221**

FIG. 2 is a front view thereof, the rear view being a mirror image thereof;

(58) **Field of Classification Search** D11/200,

FIG. 3 is a right side view thereof, the left side view being a mirror image thereof;

D11/201, 221; 24/381-383, 385-387, 414-417,
24/421-422, 427-431, 433; 2/265

FIG. 4 is a top plan view thereof;

See application file for complete search history.

FIG. 5 is a bottom view thereof; and,

(56) **References Cited**

FIG. 6 is a reference view of usage.
